UNITED STATES PATENT OFFICE

JAMES RICHARDS AND NIOLAS CORTESE, OF ARNOLD, PENNSYLVANIA

ANTICREEPER FOR RAILWAY RAILS

Application filed March 10, 1930. Serial No. 434,703.

This invention relates to an attachment for railroad rails such as is generally referred to in the prior art as an anti-creeping device, the same serving to restrict longitudinal slippage or creeping of the rails and to afford better anchorage of the rails on the adjacent cross-tie.

We are aware of the fact that many types of appliances and devices have been patented to accomplish this same result. Therefore, in carrying the present invention into practice, we have developed a new form of device which we believe is more practical and efficient than analogous prior art devices.

It follows that the principal purpose of the present invention is to provide an anti-creeping device which is susceptible of easy application and removal, which is dependable in action, an improvement upon known prior art and used appliances, and to otherwise incorporate in said device, features which will better fulfill the requirements of an invention of this classification.

In the drawings:

Figure 1 is a view in elevation and section showing the conventional rail and a portion of a tie with the anti-creeping device in operative position.

Figure 2 is a top plan view of the structure seen in Figure 1.

Figure 3 is a bottom plan view of the anti-creep, by itself.

In the drawings, in Figure 1, the cross ties are represented by the reference character 4 and the rail is generally designated by the reference character 5. The anti-creep is indicated as a unit by the numeral 6.

In developing this device we have found it feasible and expedient to form the same from a single length of heavy wire of appropriate properties, such as for instance, dependable tensile strength and yieldable maintaining and clamping action.

The wire is bent upon itself to form an upstanding handle or bail as at 7. This is of general U-shaped form and the arm portions are bent as at 8 to joint the leg portions 9 in acute angular relationship and to thereby provide keepers to engage over the adjacent

longitudinal edge of the base flange of the rail as seen clearly in Figure 1.

The fact is that by bending the arm portions of the handle in the manner shown in Figure 1, the handle is rendered susceptible of easy application and removal and secure maintenance is assured. The intermediate portions of the legs 9 are bent into resilient coils or eyes as at 10 and one of the eyes constitutes an abutment which bears against the adjacent surface of the cross tie 4.

The end portions 11 of the legs have their extremities formed with suitable shaped hooks 12 which engage over the opposite edge portions of the base flange of the rail as shown in Figure 1. Incidentally, the legs are disposed in inwardly converging relationship.

In practice, the hooks 12 are engaged over one edge of the base flange whereas the keepers 8 are engaged over the opposite edge portion. With the tie beneath the base flange one eye 10 rests against the cross tie as seen in dotted lines in Figure 2.

It has been found, because of the excessive strength of the device that it is generally necessary to use a crowbar or similar implement in placing it in position and removing it. The U-shaped configuration of the so-called handle 7 is advantageous in this respect in that it provides an appropriate rest for the crowbar so that it can be conveniently handled for forcing the handle outwardly and thereby disengaging the keepers so that the device may be bodily detached.

Then too, the coils 10 are sufficiently resilient to allow the displacement of the portions of the device to facilitate its application and removal. The fact that the device itself is clamped firmly on the rail, insures a dependable anti-creep, since the device does not slip, and since it affords an appropriate abutment for resting against the cross tie.

A careful consideration of the description in connection with the drawings will enable the reader to obtain a clear understanding of the invention and its features. Therefore, a more lengthy description is regarded as unnecessary.

Minor changes in shape, size, and rear-

angement of features and materials may be resorted to in actual practice if desired.

We claim:

1. As a new product of manufacture, an anti-creeper of the class described comprising a substantially U-shaped member formed from a single length of sturdy wire bent between its ends to form spaced converging leg portions having spring coils intermediate their ends, and retaining means at opposite ends of said leg portions, said retaining means being detachably engaged with the edge portions of the base flange of a rail.
2. As a new product of manufacture, an anti-creeper of the class described comprising a single length of wire bent between its ends to form a pair of converging spaced leg portions having their terminals formed with flange engaging hooks and having their intermediate portion formed with spring coils, and having their opposite end portions formed with a substantially arch-shaped bail constituting a handle.
3. As a new product of manufacture, an anti-creeper of the class described comprising a single length of wire bent between its ends to form a pair of converging spaced leg portions having their terminals formed with flange engaging hooks and having their intermediate portion formed with spring coils, and having their opposite end portions formed with a substantially arch-shaped bail constituting a handle, the arm portions of said bail being bent between their ends to form keepers at the juncture of the arms and legs, and to dispose the bight portion of the handle in outwardly inclined relation to provide a rest for a crowbar or the like to facilitate application and removal of the handle.

In testimony whereof we affix our signatures.

JAMES RICHARDS.
NIHOLAS CORTESE.
